UNITED STATES PATENT OFFICE

JOSEPH M. QUILL, OF LOWELL, MASSACHUSETTS, ASSIGNOR TO UNIVERSAL WINDING COMPANY, OF BOSTON, MASSACHUSETTS, A CORPORATION OF MASSACHUSETTS

BUNCH-BUILDER FOR WINDING MACHINES

Application filed July 8, 1927. Serial No. 204,358.

This invention relates to improvements in bunch-builders for winding machines. It is particularly related to bunch-building devices of the type shown and described in U. S. Letters Patent No. 1,084,459, dated January 13, 1914.

A principal object of the present improvement is to provide a device of the type specified which is capable of winding a more extended or wider bunch containing a greater yardage of yarn than that produced with the device of the prior patent above referred to.

Another object of the improvement is to provide a device of the type specified which is adjustable to wind bunches of different widths containing more or less yarns in accordance with the requirements for any particular type of loom.

Another object of the improvement is to provide a device of the type specified which will wind a firmer and more stable bunch so that the yarn will not become loosened and slough off before it is fully unwound from the bunch.

Another object of the improvement is to provide a device of the type specified which is simple in construction and adapted for use with practically all types of winding machines without alteration in the arrangement of the mechanism thereof.

Further objects of the improvement are set forth in the following specification which describes a preferred embodiment of the invention as illustrated in the accompanying drawings. In the drawings:

Fig. 1 is a plan view showing the essential elements of a well-known type of winding machine and illustrating the present improved bunch-builder as applied to use therewith;

Fig. 2 is an end view of the winding mechanism showing the relation of the operating elements of the bunch-builder with respect thereto;

Fig. 3 is a detailed view of the auxiliary thread-guide or yarn-controller which operates to lay the thread in the bunch winding;

Fig. 4 is a further detailed view of the

same showing the means for mounting the auxiliary guide; and

Fig. 5 is a fragmentary view of a portion of the automatic operating-mechanism for the yarn-releasing member which disengages the yarn from the auxiliary guide.

In the prior patent above referred to the bunch-building device comprises automatically-operated means adapted to engage and hold the yarn at the commencement of the winding of a cop or bobbin to limit its extent of traverse whereby to build a relatively narrow bunch on the bobbin or cop receiver. This means consists essentially of a swinging arm having a notch or guideway through which the yarn draws to lead it on to the bobbin while restraining it from being traversed to any considerable extent longitudinally thereof, and automatically-operated means for swinging the arm out of position after a predetermined interval to release the yarn whereby it may be traversed to the full extent to build the service winding on the bobbin. In the present improvement I make use of the automatically-operated mechanism of the prior device to effect the release of the yarn after the building of the bunch, but in lieu of the arm which is initially held in fixed relation to restrain the yarn from being traversed I employ means engaging the yarn and adapted to be reciprocated from the winding machine to impart a restricted traverse to the yarn during the building of the bunch. The automatically-operated means acts to release the yarn from the primary traversing-means at the completion of the bunch whereby the yarn is thereafter traversed to the full extent during the service winding.

Referring first to Fig. 1 of the drawings, I have here illustrated a rotating winding-spindle 2 and a reciprocating traverse-bar 3 of the same general arrangement as that disclosed in the prior patent above referred to. The winding-spindle 2 is adapted to

rotatably support a wooden bobbin or yarn receiver B which may be of any suitable form as generally employed in the shuttles of automatic or feeler looms. In such looms the feeler acts to ef-

90
95
100

fect a change of filling when the yarn has been woven off from the bobbin down to the preliminary winding or bunch, the bunch being designed to provide sufficient yarn to run while the change is being made whereby to prevent "misicks" in the weave. In the modern type of filling-replenishing loom a bunch of relatively wide extent is required in order that the feeler may properly coact therewith when the service winding is exhausted to effect replenishment of the shuttle before the yarn in the bunch has run out. As before stated, my present improved bunch-builder is adapted for winding this particular type of bunch on the naked bobbin or carrier and the width of the bunch and the amount of yarn contained therein may be regulated in accordance with requirements through adjustable means as later described.

20 In the well known type of winding machine as herein illustrated the yarn is traversed on the bobbin by means of a thread-guide 4 carried on the reciprocating traverse-bar 3. The thread-guide 4 is reciprocated with the bar 3 to the extent required to deposit the service winding on the bobbin and the guide is advanced longitudinally of the bar whereby to progressively step the layers forward to build the bobbin with a cylindrical body and a tapered nose or delivery end as illustrated by the dot-and-dash lines in Fig. 1. In some cases the winding may be in the form of a cop or quill supported on a paper or fiber tube, as distinguished from the form of bobbin herein illustrated as built up on a wooden carrier.

25 The means for rotating the winding spindle 2 and reciprocating the traverse-bar 3 are not herein described and illustrated as they may be of any suitable construction and arrangement as commonly employed in the art. The traverse-bar 3 may comprise two connected sections 5 and 6, the main portion 5 being mounted to slide in a bearing 7 and

30 projecting from the front of the frame of the machine in parallel relation with the axis of the winding-spindle 2. The threaded section 6 of the traverse-bar is joined to the section 5 by means of a pin-and-slot connection shown at 8, whereby to adapt this portion of the bar to be displaced laterally toward the winding spindle 2 in the manner and for the purpose as later explained. The outer end of the section 6 slides through a sleeve 55 or bushing 9 which is swivelled in a fixed bearing 10 to adapt this portion of the bar to swing out of alignment with respect to the portion 5.

35 The thread-guide 4 is carried on a forked arm or yoke 11 having suitable bearings 14 enclosing the bar 6 to adapt it to pivot thereon and to slide longitudinally thereof. The guide 4 is preferably made as a separate element constructed of porcelain or other vitreous material and having an extended thread-

way or guiding-groove 12 through which the yarn draws. The thread-guide 4 is advanced along the bar 6 by means of a propelling nut 15 arranged between the legs of the forked-arm or yoke 11 and adapted to engage the threads on the bar. The nut 15 carries a contact-wheel or disk 16 which is adapted to make contact with the layers of yarn deposited on the bobbin, whereby it is rotated intermittently therefrom at the end of each rearward traverse of the guide 4. This intermittent rotation of the contact-wheel 16 turns the nut 15 to gradually feed the thread-guide 4 outwardly along the traverse-bar to cause the layers of winding to be deposited in progressively advanced relation in the manner well known to those versed in the art. At the start of the winding the first layers of yarn are wound on the naked tube or bobbin and in order to bring the contact-wheel 16 into proximity therewith the rearward end of the traverse-bar section 6 is displaced laterally toward the axis of the winding-spindle. This lateral displacement of the traverse-bar section 6 to adjust the contact-wheel 16 toward the winding spindle is effected by means of a follower 17 which bears against the inclined edge 18 of an arm or finger 20, designated the cop-former. The cop-former 20 is constructed as an elbow-shaped element having a right-angled arm 19 attached to the end of the traverse-rod section 5 in any suitable manner to adapt it for adjustment thereon.

The follower 17 projects from a yoke-member 21, see Figs. 2 and 3, which has bearings 22 surrounding the rod 6 at the sides of the bearings 14 for the thread-guide arm 11. The follower 17 engages the rearward end of the cop-former 20 to maintain the end of the section 6 of the traverse-bar in the position illustrated in Fig. 1. As the thread-guide advances along the bar-section 6 the follower 17 slides outwardly on the inclined edge 18 of the former 20, thus permitting the bar-section 6 to gradually swing away from the winding-spindle until eventually it assumes a position in alignment with the main section 5. In this way the heel or foundation for the winding is built up at the base of the bobbin and thereafter the two parts of the traverse-bar are maintained in alignment to cause the contact-wheel 16 to engage with the yarn mass at its point of greatest diameter during the building of the conical layers of winding which form the cylindrical body of the bobbin. The above described construction and arrangement of the winding mechanism are well known and in common use and therefore need no further explanation herein.

In the bunch-builder of the prior patent above referred to the yarn or thread feeding to the thread-guide is diverted in its course to the winding-spindle by leading it through the restraining means which holds it from be-

ing traversed by the guide. In the present improved device instead of restraining the yarn by means of a relatively fixed arm the strand is caused to lead from the thread-guide 4 through an auxiliary guiding element 25 which is removed at some distance from the winding-spindle. This auxiliary guiding element 25 may be constructed as a wire arm or finger connected to reciprocate with the guide 4. As shown more particularly in Figs. 2 and 4 of the drawings, the yoke 21 which straddles the bearings 14 for the guide-arm 11 projects downwardly from the bar 6 in two opposite inclined legs 26 which are connected at the bottom by a cross-strip 27 forming a step or mounting for supporting the auxiliary guide-arm 25. The terminal portions of the legs 26 are provided with a hook or loop 28 which straddles a fixed rod 29 constituting a track or guideway therefor to maintain the yoke 21 in vertical relation.

The auxiliary guide 25 may conveniently be constructed in the form of a wire arm having a flattened plate 30 at its rearward end adapted to seat on the step 27 in position between the legs 26 of the yoke 21, see Figs. 3 and 4. In the plate 30 are suitable holes 31, any one of which may be engaged by a bolt 32 to fixedly secure the guide 25 in position on the yoke 21 and to adapt it for adjustment to regulate its operative length for a purpose as later explained. The outer end of the wire arm or guide 25 is bent into off-set relation with respect to its main length and curled around to form a loop 33 adapted to receive the strand of yarn or thread *y* to direct it on to the barrel of the bobbin B. It will be noted by reference to Fig. 1 of the drawings that the loop 33 on the guide-arm 25 is disposed at some distance away from the winding-spindle so that as the auxiliary guide is traversed with the thread-guide 4 the yarn will extend in a free length between the point at which it is guided and the surface on which it is being wound. Consequently, the strand will have a certain amount of play between the auxiliary guide and the bobbin so that the extent to which it is traversed on the bobbin will be less than the full extent of movement of the guide, as will later more fully appear from the explanation of the operation of the device. It will be observed from Fig. 2 of the drawings that the strand *y* leads up from a source of supply, not herein illustrated, and passes through the guiding groove 12 in the thread-guide 4 before it is led through the loop 33 in the auxiliary guide 25. The yarn is threaded through the guides in this manner at the start of the winding, but

remains engaged with the auxiliary guide 25 only during the winding of the bunch on the bobbin, being thereafter released to feed from the main guide 4 direct to the bobbin. The means for releasing the yarn from the auxiliary guide 25 at the completion of the

bunch winding will next be described. As illustrated in Figs. 1 and 2, it comprises essentially a curved finger or sickle-shaped arm 35 which is normally held away from the path of the yarn during its traverse by the auxiliary guide 25 and is shifted or thrown into position to act on the yarn to disengage it from the guide loop 33. The releasing finger 35 may be operated from any suitable instrumentalities, and conveniently I make use of the automatic mechanism shown in the prior patent above referred to as employed for shifting the yarn-restraining means. The automatic operating-mechanism may be contained in a casing 36 suitably attached to the frame 13 of the winding machine. In the present embodiment of the invention the releasing finger 35 has a straight arm 37 which is fastened with bolts 38 or otherwise suitably attached to the end of an arm or lever 40 to project at right-angles thereto. The lever 40 is pivoted on a stud 41 fastened to the casing 36 and has a right-angled extension or arm 42 which normally bears against the periphery of a rotatable cam 43. The cam 43 is journaled on a stud 44 and carries with it a ratchet wheel 45 having a series of teeth 46 extending throughout a portion of its circumference and terminating at one end in a radial projection or stop-finger 47. The stop-finger 47 is normally engaged by a pawl 48 which is pivoted on the pivot-stud 41 for the lever 40. A coil spring 50 surrounds the bearing stud 44 for the cam 43 with one end hooked through a hole in the cam so that normally it tends to rotate the cam and ratchet 45 in a clockwise direction, the extent of this rotation being limited by the engagement of the pawl 48 with the detent or stop-finger 47.

The ratchet 45 is rotated in a contra-clockwise direction by means of a pawl 51 which engages successively with its teeth 46 during the reciprocation of the pawl from an arm 52. As the ratchet turns the first pawl 48 engages with its teeth 46 to prevent retrogressive movement thereof, the two pawls being connected by a spring 53 to hold them in engagement with the teeth. A finger 62 on the pawl 51 is adapted to be engaged by the side of the lever 40 to release the pawl from the ratchet 45 when the lever is manually returned to first position.

The pawl 51 is pivoted to the arm 52 by means of a stud 54, while the arm itself is rockably mounted on a stud 49 screwed into the lever 40. The arm 52 reaches across one end of the casing 36 and slides in a slot 55 formed in the bent up end of the latter. A spring 56 hooked into a projection 57 on the opposite end of the arm 52 and anchored to the casing 36 tends to maintain the arm in the position illustrated in Fig. 1 with its edge bearing against the end of the slot 55. The spring 56 also tends to rock the lever 40 when

its arm 42 is released from the periphery of the cam 43 in the manner as later explained. The outer end of the arm 52 carries a plate or bumper 58 adapted to be engaged by the side of the arm 19 which connects the former 20 with the end of the traverse-bar section 5. As the bar 5 is longitudinally reciprocated the arm 19 of the former 20 comes into engagement with the bumper 58 at each rearward stroke of the bar, thereby acting to rock the arm 52 to cause the pawl 51 to turn the ratchet 45 through the distance of one tooth. As the ratchet is turned in a counter-clockwise direction the pawl 48 engages successively with its teeth to prevent it from turning back and the cam 43 is rotated with the ratchet while the arm 42 of the lever 40 rides on its periphery. Referring to Fig. 5 of the drawings, it is to be noted that the cam 43 has a cut-away section at 59 to allow the end of the arm 42 to slide across its axis. It is also to be noted that the pawl 48 has a finger 60 bent down to engage against the side of the arm 42, so that when the lever 40 is swung back into its initial position the pawl will be released from the ratchet 45 to allow the latter to be turned back until its detent 47 engages with the end of the pawl. The method of operation of the complete device will now be explained in detail.

To prepare the machine for winding the thread-guide 4 is adjusted in position adjacent the butt end of the bobbin B by sliding the yoke 11 back to the rearward end of the traverse-bar section 6, the nut 15 being released from the threads on the bar in the usual manner for this purpose. This adjustment of the thread-guide causes the follower 17 to slide up the inclined edge 18 of the cop-former 20 so that the end of the bar section 6 is swung inwardly toward the axis of the winding-spindle 2. This brings the periphery of the contact-wheel 16 in proximity to the surface of the barrel of the bobbin B so that it will be caused to contact with the first layer of winding wound on to the barrel.

The strand *y* of thread or yarn is led up from its source of supply, carried through the groove 12 in the thread-guide 4 and thence drawn out around the loop 33 at the end of the auxiliary guide 25. The end of the yarn is then led back to the barrel of the bobbin B and suitably secured thereto by tying or winding it therearound.

The winding machine is started to operate and the winding-spindle 2 rotates the bobbin B to wind on the strand as it feeds from the auxiliary guide 25. Concurrently with the rotation of the spindle 2 the traverse-bar 3 is reciprocated to cause the thread-guide 4 to traverse back and forth longitudinally of the bobbin. The auxiliary guide 25 being carried with the guide 4 is thus also traversed longitudinally of the bobbin B,

but, since, as before explained, the strand *y* leads from the guiding loop 33 to the bobbin B in a free length its traverse on the barrel of the bobbin will be somewhat less than the full extent of reciprocation of the thread-guide 4 as indicated by the dot-and-dash lines in Fig. 1; the full lines representing the position of the guide 25 at the end of its outward traverse and the dotted lines illustrating its position at the end of its inward traverse. The strand *y* is thus caused to wind on to the bobbin in layers of restricted traverse to build a bunch indicated by the reference character *b*.

During this initial winding of the bunch on the bobbin B the yarn-releasing finger 35 remains fixed in the position shown by full lines in Fig. 1, the finger extending downwardly toward the axis of the winding-spindle 2 as shown more particularly in Fig. 2, but being out of the path of the length of yarn leading from the guide 25 to the bunch. The yarn-releasing finger 35 is held in this position by engagement of the arm 42 on the lever 40 with the periphery of the cam 43. As the bunch winding proceeds the arm 52 is operated from the reciprocating movement of the traverse-bar 3 to cause it to actuate the pawl 51 to intermittently rotate the ratchet 45 and thereby the cam 43. At each rearward stroke of the traverse-bar section 5 the arm 19 of the former 20 strikes against the bumper 58 to swing the arm 52 to the left as viewed in Fig. 1, and as the bar 5 moves in the opposite direction the spring 56 returns the arm 52 back to first position whereby to engage the pawl 51 with another tooth on the ratchet. After a predetermined number of oscillations of the arm 52 the pawl 51 will have turned the ratchet 45 sufficiently to bring the cut-out portion 59 of the cam 43 into the position illustrated in Fig. 5 of the drawings, and at this point the arm 42 on the lever 40 is allowed to slide across the axis of the cam as the lever is rocked under the tension of the spring 56. Through this action of the automatic mechanism the yarn-releasing finger 35 is swung back to the position illustrated by dash lines in Fig. 1.

The release of the arm 40 occurs at the end of the rearward stroke of the traverse-bar 5 when the thread-guide 4 is at the rearward end of its traverse with the auxiliary-guide 25 in the position illustrated by dotted lines in Fig. 1. Consequently, as the finger 35 swings back from the bobbin B its curved edge will engage with the strand *y* drawing through the loop 33 of the guide 25 as indicated by the dotted representation of the finger in Fig. 1. The continued movement of the finger 35 will therefore lift the strand *y* out of the loop 33 to free it from the guide 25. Now as the traverse-bar 5 slides outwardly toward the end of the winding-spindle 2 the strand *y*

will slide off from the end of the finger 35 and the loop or bight of yarn extending between the thread-guide 4 and the bobbin B will thus be released. As the slack in the loop 5 is taken up by the winding the strand will feed direct from the groove 12 in the thread-guide 4 to the barrel of the bobbin B. In this manner when the bunch winding is completed the yarn is released from the auxiliary 10 guide 25 so that thereafter it will feed to the bobbin from the guide 4 to be laid on the bobbin with the full extent of traverse of the guide. The machine will thereafter continue 15 to operate to lay the yarn on the bobbin with the full extent of traverse to build the service winding forming the main body of the bobbin which is constituted by a series of conical layers stepped progressively forward toward the tip end of the spindle 2.

20 When the bobbin is completed in the form illustrated by dot-and-dash lines in Fig. 1 it is doffed from the spindle 2 and an empty carrier placed thereon. The thread-guide 4 is then returned to its initial position on the 25 traverse-bar 3 in the manner as before explained and the yarn-releasing finger 35 is adjusted out of range of action. In setting the yarn-releasing finger 35 the lever 40 is rocked manually into the position shown in Fig. 1 30 where it is held by the return of the cam 43 to first position. The return of the cam 43 is effected by the release of the pawls 48 and 51 from the teeth on the ratchet 45 under the rocking action of the lever 40. As the lever 35 40 is swung back into first position the edge of its arm 42 engages with the lug 60 on the pawl 48 to rock the pawl away from the ratchet teeth 46. Concurrently therewith the outer end of the lever 40 engages with the 40 finger 62 on the pawl 51 to also release this pawl from the teeth 46. As the lever 40 is held for an instant to cause this release of the pawls 48 and 51 the ratchet 45 is turned back under the tension of its spring 50 until 45 its stop-finger 47 strikes against the end of the pawl 48. The lever 40 can then be released and the parts will assume and be held in cooperative relation as illustrated in Fig. 1 to provide for the automatic operation of 50 the yarn-releasing finger 35 at the completion of the next bunch wound.

It will be observed from the above that the present improvement provides a simple and efficient mechanism for effecting the winding 55 of a bunch on the bobbin having a suitable width and the proper length of yarn contained therein in accordance with the requirements of present type feeler looms.

To vary the width of the bunch the auxiliary-guide arm 25 may be adjusted on its carrying-member or yoke 21 to set the guiding-loop 33 at a greater or less distance away 60 from the axis of the winding-spindle 2. It is obvious that as the guiding-loop 33 is moved away from the spindle 2 the range

of play of the yarn leading from the loop to the bobbin will be increased so that the extent of traverse of the yarn on the bobbin will be correspondingly restricted. On the other hand, as the guiding-loop 33 is adjusted toward the winding-spindle the yarn will have less play between the auxiliary guide and the bobbin and therefore its traverse will be increased and the bunch wound with a more extended width. The greater the extent of the bunch the greater the length of yarn contained therein, so that in this way the yardage in the bunch winding may be controlled as desired. As a further means of regulating the amount or length of yarn wound into the bunch the ratchet 45 may be adjusted angularly of the cam 43 to require a greater or less number of reciprocations of the traverse-bar 5 before the lever 40 is released. The yarn-releasing finger 35 may therefore be caused to act after any certain number of reciprocations of the traverse-bar 5 to disengage the strand from the auxiliary guide 25 after a predetermined number of revolutions of the winding-spindle 2.

As a further feature of improvement the present device operates to form a firmer and more stable bunch which will not slough off when the bobbin is being unwound in the shuttle.

While I have herein described and illustrated my improved bunch-building device as embodied in a preferred form of mechanism and applied to use in connection with a certain type of winding machine, it is to be understood that modifications may be made in the construction and arrangement of the device and in its adaptation to winding machines of other types without departing from the spirit or scope of the invention. Therefore, without limiting myself in this respect, I claim:

1. In a winding machine, the combination of means for initially winding yarn on a bobbin with a restricted traverse to build a bunch, means for laying the yarn with a longer traverse to build the service winding, and mechanically-actuated means operated upon the completion of the bunch to shift the yarn from the bunch-winding means to the service-winding means.

2. In a winding machine, the combination of means for traversing yarn on a bobbin to wind a bunch of predetermined width, means for winding the yarn with a longer traverse to build the service winding, and means actuated from the traversing-means upon the completion of the bunch to transfer the yarn from the bunch-winding means to the service-winding means.

3. In a device of the type specified, the combination of a rotating winding-spindle, means for traversing yarn on the spindle to wind a bunch, means for winding the yarn with a longer traverse to build a bobbin on the

spindle, and means actuated from the traversing-means at a predetermined point in the winding to transfer the yarn from the first traversing-means to the second traversing-means.

4. In a device of the type specified, the combination of a rotating winding-spindle, guiding-means for traversing yarn or thread to wind a bobbin on the spindle, an auxiliary guide for traversing the yarn with a restricted traverse to build a bunch at the start of the winding, and means actuated from the winding means to transfer the yarn from the auxiliary guide to the main guiding-means after the completion of the bunch.

5. In a winding machine, the combination of a winding-spindle, a thread-guide for traversing yarn to wind a cop or bobbin on the spindle, an auxiliary guide for winding the yarn with a restricted traverse to build a bunch at the start of the winding, and means automatically moved into position to transfer the yarn from the auxiliary guide to the main thread-guide at the completion of the bunch.

6. In a device of the type specified, the combination of a winding-spindle, a thread-guide for traversing yarn to wind a cop or bobbin on the spindle, controlling-means on the thread-guide for restricting the extent of traverse of the yarn at the start of the winding to build a bunch on the bobbin, and means for releasing the yarn from said controlling-means at the completion of the bunch to adapt it to be traversed by the thread-guide to the full extent to wind the main portion of the bobbin.

7. In a device of the type specified, the combination of a winding-spindle, a thread-guide for traversing yarn to wind a cop or bobbin on the spindle, an auxiliary guide carried with the thread-guide and adapted to engage the yarn at the start of the winding to feed it to the bobbin with a restricted traverse to build a bunch, and means for automatically disengaging the yarn from the auxiliary guide to adapt it to be traversed by the thread-guide to the full extent to build the body of the bobbin.

8. In a device of the type specified, the combination of a winding-spindle and thread-guide arranged to be reciprocated one with respect to the other, an auxiliary guide through which the yarn leads at the start of the winding to restrict its traverse to build a bunch, said auxiliary guide having a relative reciprocation with respect to the winding-spindle, and means operative on the yarn to release it from the auxiliary guide at the completion of the bunch whereby it may be traversed from the thread-guide to build the body of the bobbin.

9. In a winding machine, the combination of a winding-spindle and thread-guide adapted to be reciprocated one with respect to the

other to traverse yarn or thread to wind a cop or bobbin, an auxiliary guide adapted to traverse the yarn to a limited extent at the beginning of the winding to build a bunch on the bobbin, and automatically-operated means for engaging the yarn to release it from the auxiliary guide whereby it is fed from the thread-guide to be traversed to the full extent to wind the main portion of the bobbin.

10. In a winding machine, the combination of a winding-spindle, a reciprocating thread-guide for traversing yarn to wind a cop or bobbin on the spindle, an auxiliary guide reciprocated with the thread-guide in a path remote from the bobbin to cause the yarn to be wound with a restricted traverse to build a bunch, and means to release the yarn from the auxiliary guide at the completion of the bunch whereby it will feed from the thread-guide to be traversed to the full extent to wind the body of the bobbin.

11. In a winding machine, the combination of a winding-spindle, a thread-guide reciprocable longitudinally of the spindle to traverse the yarn to wind a cop or bobbin thereon, an auxiliary guide reciprocable with the thread-guide at a point removed from the winding-spindle and adapted to control the yarn to cause it to feed to the winding-spindle with a restricted traverse to build a bunch on the bobbin, and means for releasing the yarn from the auxiliary guide to adapt it to be traversed to the full extent by the thread-guide.

12. In a winding machine, the combination of a winding-spindle, a thread-guide reciprocable longitudinally of the spindle to wind a cop or bobbin thereon, an auxiliary guide extending rearwardly from the thread-guide and adapted to control the yarn as it leads from the thread-guide to the bobbin to restrict the extent of its traverse whereby to wind a bunch, and means for releasing the yarn from the auxiliary guide to adapt it to feed from the thread-guide directly to the bobbin to be traversed to the full extent thereon.

13. In a winding machine, the combination of a winding-spindle, a thread-guide reciprocable opposite the spindle to wind a cop or bobbin thereon, an auxiliary guide movable with the thread-guide and adapted to control the yarn to restrict the extent of its traverse at the start of the winding to build a bunch, and means adapted to be thrown into the path of the yarn as it is traversed from the auxiliary guide to release it therefrom whereby the yarn is traversed by the thread-guide to the full extent to wind the main portion of the bobbin.

14. In a winding machine, the combination of means for traversing yarn on a bobbin to wind a bunch of predetermined width, means for winding the yarn with a longer traverse

to build the service winding, and means adapted to engage the yarn at the completion of the bunch to release it from the bunch-winding means whereby it is traversed to the 5 full extent to build the main portion of the bobbin.

15. In a winding machine, the combination of means for traversing yarn on a bobbin to a limited extent to build a bunch, other means 10 for traversing the yarn to a greater extent to build the service winding, and means acting on the yarn at the completion of the bunch to release it from the first traversing-means to adapt it to be traversed to the full extent 15 by the second means to build the body of the bobbin.

16. In a winding machine, the combination of a winding-spindle, a thread-guide adapted to be reciprocated adjacent the spindle to 20 traverse the yarn to wind a bobbin thereon, an auxiliary guide reciprocable with the thread-guide in a path at a distance from the spindle, a yarn-releasing member normally out of the path of the traversing yarn, and 25 means to operate said releasing-member after a predetermined number of reciprocations of the thread-guide to cause it to release the yarn from the auxiliary guide whereby it is traversed directly by the thread-guide.

30 17. In a winding machine, the combination of a winding-spindle, a thread-guide arranged adjacent the spindle and reciprocable longitudinally thereof, an auxiliary guide carried with the thread-guide and extending to a point remote from the spindle, a yarn-releasing member, and means for operating said member to cause it to engage the yarn to release it from the auxiliary guide at a predetermined point in the winding.

40 18. In a winding machine, the combination of a winding-spindle, a thread-guide reciprocable longitudinally of the spindle to traverse the yarn on a cop or bobbin, an arm extending rearwardly from the thread-guide 45 and provided with means at its end for controlling the yarn as it feeds from the thread-guide to the winding-spindle, a yarn-releasing member, and means for operating said member to cause it to release the yarn 50 from the controlling means whereby it is caused to feed directly from the thread-guide to the bobbin being wound.

55 19. In a winding machine, the combination of a winding-spindle, a thread-guide reciprocable opposite the spindle, an arm extending from said thread-guide and provided with an auxiliary guide at its end through which the yarn is adapted to lead as it feeds 60 from the guide to the bobbin on the spindle, and a releasing-member adapted to be thrown into the path of the yarn to disengage it from the auxiliary guide whereby it will feed direct from the main guide to the bobbin 65 being wound.

20. In a winding machine, the combination with a winding-spindle, a thread-guide reciprocable opposite the spindle, an auxiliary guide reciprocable with the thread-guide and disposed at a distance away from the winding-spindle, a yarn-releasing member adapted to be set in position out of the path of the 70 yarn as it is traversed by the auxiliary guide, and automatically-operated means for moving said arm across the path of the yarn to release it from the auxiliary guide after a predetermined interval of winding.

In testimony whereof I hereunto affix my signature.
